UNITED STATES PATENT OFFICE.

WILLIAM M. SAGAR AND LESTER W. SAGAR, OF BROOKLYN, NEW YORK.

CUTTING DEVICE.

1,095,032.

Specification of Letters Patent. Patented Apr. 28, 1914.

Application filed July 23, 1912. Serial No. 711,167.

To all whom it may concern:

Be it known that we, WILLIAM M. SAGAR and LESTER W. SAGAR, citizens of the United States, residing at Brooklyn, in the county 5 of Kings and State of New York, have invented certain new and useful Improvements in Cutting Devices, of which the following is a specification, reference being had therein to the accompanying drawing.

10 This invention relates to certain new and useful improvements in cutting apparatus and is designed particularly for use in cutting down the mica between commutator segments.

15 The supporting frame is provided with beads serving the double purpose of a grip and as a reinforcement for the frame.

We provide means of adjustment whereby 20 the apparatus is adapted for use in connection with any size of commutator and also make provision for limiting the depth of the cut of the saw.

25 Other objects and advantages of the invention will hereinafter appear and the novel features thereof will be particularly pointed out in the appended claims.

The invention is clearly illustrated in the accompanying drawings, which, with the numerals of reference marked thereon, form 30 a part of this specification, and in which—

Figure 1 is a top plan with the cover removed. Fig. 2 is a front elevation showing the machine in cutting position on a commutator. Fig. 3 is a longitudinal section as on the line 3—3 of Fig. 1. Fig. 4 is a side elevation showing the cutting means. Fig. 5 is a side elevation showing the adjusting means, and Fig. 6 is a cross section on the line x—x of Fig. 3 looking in 35 the direction of the arrows.

40 Like numerals of reference indicate like parts throughout the several views.

Referring to the drawings, 1—1 designates the main frame preferably provided 45 with a removable top, not shown. Around the edges of the frame is the beading 3 which serves as a grip and also as a reinforcing means for said frame. Extending transversely of this frame there is a power 50 receiving shaft 4, mounted in the bearings 5—5 and adapted to be lubricated by the oil cups 6—6 placed on the said bearings 5—5. Motion is imparted to this shaft by means of a flexible shaft 7 which is connected to the end of said shaft 4 with projections beyond the frame, the shaft 7 de-

riving power from any suitable source not shown. The point of connection between the ends of these shafts is protected by a suitable guard or housing 8.

Extending from the shaft 4 are the arms 9—9 substantially parallel with each other and which support a second shaft 10 at their outer ends, which latter shaft is parallel with the shaft 4. This shaft 10 is the saw 65 shaft, 11 being the saw which preferably is affixed to said shaft beyond one side of the main frame, as seen clearly in Figs. 1, 2 and 6. This shaft is lubricated by the oil cups 5^a—5^a placed on the bearings 4^a—4^a 70 of said shaft 10. 11^a is a guard for said saw, as seen in Figs. 1 and 2.

12 and 13 are pulleys rigidly affixed to or integral with the shafts 4 and 10 respectively, 14 being a drive belt running over 75 said pulleys, as seen in Figs. 1, 2 and 3, so that when motion is imparted to the power receiving shaft 4 through the medium of the shaft 7, the saw shaft 10 is caused to revolve, thus revolving the cutting saw 11. 80 Any desired tension may be placed upon the belt 14 by the idler 15 and the idler spring 16 on the transverse shaft 16^a, as shown clearly in Fig. 3. This saw shaft 10, which we term a floating shaft, and the saw 85 11 are held to their work by the springs 17—17 which are secured to the inner sides of the frame, their free ends pressing downward upon the arms 9—9, as will be best understood upon reference to Figs. 3, and, 90 when cutting, should the machine happen to encounter an unusually hard substance, these springs will give and allow a sufficient amount of yield, thus taking any strain 95 away from the mechanism and avoiding injury thereto.

To limit the downward movement of the saw shaft and saw, there are secured to the arms 9 the brackets 18—18, as seen in Figs. 1 and 3, through which pass the screws 100 19—19, the ends of which rest upon or bear against the lugs 20—20 projecting from the inside of the frame 1—1. These lugs serve as rests for the saw shaft 10 and permit of varying the depth of the cut of the 105 saw, the saw shaft being raised or lowered as may be required by operating the screws 19—19. Thus, while the springs 17—17 press downward upon the arms 9—9, the lugs 20—20 prevent the shaft from going any 110 lower than desired.

One end of the shaft 10 passes through a

vertical slot 21 on one side of the frame 1—1, as seen in Figs. 4 and 6, which is of sufficient height to allow the shaft to be raised or lowered, the shaft being shown in Fig. 6 as in its lowermost position.

In order to permit of the adjustment of the apparatus to any size of commutator, there is provided the side piece 24, seen best in Fig. 2, which is adjustable vertically by means of the slots 24^a and the screws 24^b, as seen in Fig. 5. It will thus be seen that by raising or lowering this side piece, the device is adapted to fit the commutator which is to be operated upon.

22 in Fig. 2 designates a portion of the commutator. When the apparatus is placed upon a commutator, as shown in Fig. 2, a stop 23 is employed to keep the device from slipping. This stop is adapted to be engaged by the side piece 24, as seen in Fig. 2.

In order to prevent any lateral movement of the saw shaft 10, there is provided the collar 10^a, as seen in Fig. 6, which is placed on the saw shaft on the outside of one side 25 of the main frame 1—1, and the arm 9 on the inside of the same side of the frame, the side of the frame being thus clamped between said collar and the arm 9, as will be clearly understood upon reference to said 30 Fig. 6.

With the parts constructed and arranged substantially as hereinbefore described, the operation will be apparent, especially when taken in connection with the annexed drawings. Briefly stated, it is as follows: The stop 23 is placed in position upon the commutator, the side piece 24 is properly adjusted and the saw 11 entered between two segments to operate upon the mica. Power 40 is then applied to the shaft 7 and, consequently, to the shaft 4, and by means of the belt 14 and the pulleys 12 and 13, the saw shaft 10 is actuated to revolve the saw. When the mica between these two segments 45 has been cut to the required depth, the device is moved to the mica between the next two segments, and so on. As seen in Fig. 2, the mica between the segments to the right of the one upon which the saw is shown as 50 operating, have all been cut. The one to the left of the saw has not yet been operated upon.

What is claimed as new is:—

1. In a device of the class described, a frame provided with a fixed shaft, and a floating shaft carrying a saw swingingly connected to the fixed shaft, said floating shaft provided with tension springs for forcing the saw downward, said main frame having a slot through which said floating shaft passes.

2. In a device of the class described, a frame provided with a fixed shaft, a floating shaft swingingly connected to the fixed shaft and carrying a saw, said floating shaft

provided with tension springs for forcing the saw downward, said main frame having a slot through which said floating shaft passes, and means to limit the downward movement of said floating shaft.

3. In a device of the class described, a frame provided with a fixed shaft, a floating shaft swingingly connected to the fixed shaft and carrying a saw, said floating shaft provided with tension springs for forcing the saw downward, said main frame having a slot through which said floating shaft passes, and means for raising and lowering said floating shaft.

4. In a device of the class described, a frame provided with a fixed shaft, a floating shaft swingingly connected to the fixed shaft and carrying a saw, pulleys mounted on each shaft, a drive belt connecting the pulleys, tension springs for the floating shaft, said main frame having a slot through which said floating shaft passes, and means for varying the depth of the saw cut, said means consisting of brackets extending from the shaft supporting arms and adjusting means passing through said brackets and resting upon lugs upon the inside of the frame.

5. In a device of the class described, a frame, an extension member secured to one side of said frame, means to hold said extension member in adjusted position, a fixed power-receiving shaft, a guard for said shaft, a floating shaft swingingly connected to the fixed shaft by shaft supporting arms 100 and carrying a saw, a guard for said saw, pulleys cast integral with each shaft, connecting means for the pulleys, tension springs for the floating shaft for forcing said shaft downward, said main frame having a slot through which the floating shaft passes, and means for varying the depth of the saw cut, said means consisting of brackets on the shaft supporting arms, screws passing through said brackets and engaging 110 lugs upon the inside of the frame.

6. In a device of the class described, a frame, grips on said frame, means for varying the width of one side of said frame, a main power-receiving shaft, a guard for said shaft, a floating shaft carrying a saw, a guard for the said saw, arms pivotally connecting the floating shaft to the power receiving shaft, springs pressing downward upon said arms, brackets extending from the said arms, set screws passing through said brackets and resting upon lugs projecting from the inside of the frame, pulleys integral with the fixed shaft and the floating shaft and a drive belt connecting the pulleys.

7. In a device of the class described, a frame, grips on said frame, one side of said frame being adjustable up and down, a main power receiving shaft, a floating shaft car-

rying a saw, connected to the fixed shaft by arms, means for urging said floating shaft in one direction, and means for varying the depth of the saw cut, said means consisting of brackets upon the shaft supporting arms and set screws passing through said brackets and resting upon lugs upon the inside of the frame, said frame having a slot through which said floating shaft passes

and means for transmitting motion from the power receiving shaft to the floating shaft.

In testimony whereof we affix our signatures, in presence of two witnesses.
